CLAIM

The ornamental design for a goods-to-person station as shown and described.

DESCRIPTION

FIG. 1 is a front perspective view of a goods-to-person station showing the new design;

FIG. 2 is a front elevation view thereof;

FIG. 3 is a rear elevation view thereof;

FIG. 4 is a right side elevation view thereof;

FIG. 5 is a top plan view thereof; and,

FIG. 6 is a bottom plan view thereof.

The broken lines illustrate portions of the goods-to-person station that form no part of the claimed design.

The broken lines illustrate portions of the goods-to-person station that form no part of the claimed design.

1 Claim, 6 Drawing Sheets
